TONE SHAPING CIRCUIT

Francis M. Schmidt, North Tonawanda, N. Y., assignor to The Rudolph Wurlitzer Company, North Tonawanda, N. Y., a corporation of Ohio

Application June 1, 1949, Serial No. 96,546

6 Claims. (Cl. 84—1.12)

1

This invention relates to frequency discriminating networks and more particularly to tone shaping circuits incorporated in an amplifier used in conjunction with an electronic musical instrument such as an electronic organ.

In musical instruments in general it is often desirable to emphasize or to suppress certain qualities of musical tones. In electronic organs, for instance, it is desirable to accentuate the output of certain regions in the frequency spectrum for one group of tone generators while it is desirable to emphasize the output of other groups of tone generators in other regions.

Among the important objects of this invention is the selective shaping of the outputs of various groups of tone generators in an electronic organ.

Another object of this invention is to provide means by which the amplitude of certain musical tones may be altered in accordance with the requirements of the different acoustical phenomena encountered in various electronic organ installations.

Another object of this invention is to provide selective emphasis or discrimination of groups of musical tones in an electronic organ to agree with individual taste.

Other and further objects and advantages of the present invention will be apparent from the following description when taken in conjunction with the accompanying drawings in which:

Fig. 1 is a fragmentary partially schematic end view of an electronic organ in which this tone shaping circuit may be utilized;

Fig. 2 is a schematic wiring diagram of a preferred embodiment of the tone shaping circuit; and

Fig. 3 is a family of curves illustrating the relative output wave forms of the tone shaping circuit described.

Fig. 1 is a fragmentary end view of an electronic organ 1 having a plurality of hand actuated keyboards or manuals 3 and a pedal keyboard 5. A plurality of tone generators 7 are preferably of the vibrating reed type described by Hoschke in his Patent No. 2,015,014 in which the changing capacitance between a vibrating metallic reed and a plurality of adjacent screws generates a musical tone. A blower 9 supplies air to a wind chest 11 and pallet valves 13 admit air to the tone generators from the wind chest. The output of the tone generators 7 is connected to an amplifier 15 which includes the tone shaping circuit which is the subject of this invention. The amplifier also has associated with it a volume

control 16 actuated by a foot pedal 17. The interconnections between the tone generators and amplifier are controlled by a coupler board 19 and a second coupler board 21 may control the operation of the pallet valves in response to the operation of the various keys. A bank of stop tablets 23 may control the operation of the coupler boards 19 and 21.

As described in the aforementioned patent to 10 Hoschke, the reeds comprising the tone generators may be prevoiced to give effects such as flute tones, string tones, etc. One group of reeds prevoiced to simulate flute tones may be electrically connected in parallel as is diagrammatically represented at 25 in Fig. 2 and connected to a positive source of potential and to ground through a resistance capacitance network 27. The adjacent elements which in conjunction with each of the 15 vibrating reeds comprises a series of capacitors 29 may all be connected in parallel as is diagrammatically illustrated at 29 in Fig. 2. In like manner other groups of similar prevoiced reeds are connected in parallel as the pedal reeds 31, viola reeds 33, and diapason reeds 35, and they are likewise connected to a positive source of potential 20 and to ground through resistance capacitance networks 27. The cooperating capacitance elements of the last named groups are connected in 25 parallel groups and are illustrated diagrammatically in Fig. 2 as 31, 33 and 41, respectively.

The outputs of the flute, pedal and diapason banks of tone generators are connected through suitable isolating and voltage dividing networks to an amplifier tube 43. The networks comprise 30 a plurality of resistors 45, 47, 49, 51 and 53 and a capacitance 55, all of which in combination with the varying capacitance of the tone generators determine the alternating current voltage impressed on the grid of the amplifier tube 43. The amplifier tube 43 is provided with a cathode bias resistor 57 and cathode capacitor 59 in the usual manner and plate potential is supplied through a plate load resistor 61 from a suitable 35 source of positive direct current potential.

The output potential of the viola tone generators is connected to the grid of a second amplifying tube 63 through a resistor 65. A resistor 67 is connected between the viola tone generators and the resistor 65 and to ground. The resistors 65 and 67 provide isolation and determine the value 40 of potential applied to the grid of the tube 63. A cathode resistor 69 and a capacitor 71 in parallel therewith provide cathode bias for the amplifier tube 63 in the usual manner. Plate potential for the tube 63 may be supplied through the resistor

13 which may be connected to the same source of positive direct current potential.

The outputs of the two amplifier tubes 43 and 63 are combined through networks to be described later to excite the grid of a combined amplifier tube 75 which is cathode biased by means of a cathode resistor 77 and cathode condenser 79 connecting the cathode to ground. The output circuit of the tube 75 may be conventional and is consequently not shown. A resistor 81 and capacitor 83 are connected in series with the plate of the tube 63 and the grid of the tube 75. The plate of the amplifier tube 63 is also connected to the grid of the combining amplifier tube 75 by means of a capacitor 85 and resistors 87 and 89. The plate of the amplifier tube 43 is connected to the grid of the combining amplifier tube 75 through a capacitor 91, resistor 93 and the aforementioned resistor 89. A resistor 95 is connected at one end to the junction between resistors 89 and 93 and at the other end to a resistor 97 and capacitor 99. The resistor 97 and capacitor 99 are connected in parallel and are grounded. A movable tap switch arm 101 is connected to the junction between resistors 95 and 97 and selectively engages tap switch contacts 103, 105 and 107. The tap switch contact 103 is an open contact and the tap switch contacts 105 and 107 are connected to ground through capacitors 109 and 111 respectively.

Curve A in Fig. 3 is indicative of the output response of the amplifier when the grid of the tube 63 is excited. The constants of the resistor 81 and capacitor 83 are such as to offer a low impedance to the higher frequencies and a relatively high impedance to the lower frequencies so that the higher frequencies are relatively emphasized.

The bass frequencies in the output circuit of the amplifier tube 63 pass through a low impedance path including capacitance 85 and resistor 87 to the grid of the tube 75 where combined with the output of tube 43 they become essentially a part of curve B which represents the overall amplifier response if input is applied to the grid of tube 43. Curve B likewise illustrates that the circuit comprising resistors 95 and 97 and capacitors 99, 109 and 111 emphasizes the bass frequencies while relatively discriminating against the higher frequencies. It is relatively more difficult to hear the low frequencies at certain volume levels varying to some extent with the installation and consequently the tap switch 101 which aids in accentuating the low frequencies may be termed a pedal compensator. Movement of the tap switch arm 101 to the higher number tap switch contacts 105 and 107 increases the emphasis on the bass as shown by curves C and D and may be preset when the electronic organ is installed.

It is evident that the tone shaping circuit herein described modifies the output wave shape of the tone generators in conformance to desired requirements by selectively accentuating or discriminating against portions of the output tones, the selective pedal compensator or tap switch permitting adjustment of response in accordance with the acoustical requirements of a given location or individual taste.

It is obvious that various changes may be made in the details of construction in the example shown, and I therefore intend to be limited only by the spirit and scope of the following claims.

I claim:

1. In an electronic musical instrument having

a plurality of tone generators each producing a tone of complex quality, a tone shaping circuit comprising a plurality of substantially parallel electronic amplification means, each of said means accentuating certain portions of the complex output of each of said tone generators while relatively discriminating against other portions, and electronic means for combining the outputs of said tone generators to form a composite tone.

2. A tone shaping circuit as defined in claim 1 in which one of said substantially parallel amplifying means includes means for relatively emphasizing the lower frequencies and another of said amplifying means includes means for relatively emphasizing the higher frequencies.

3. In an electronic musical instrument having a plurality of musical tone generators each producing a tone of complex quality, a tone shaping circuit comprising an electronic tube, an electrical network including resistances and reactances interconnecting the control element of said electronic tube and some of the tone generators to provide isolation therebetween and determine the alternating current potential applied to said control element, an output circuit for said electronic tube, a second electronic tube and a network connecting said output circuit and the control element of said second vacuum tube, said network including reactances and impedances to relatively emphasize certain frequencies while discriminating against others of each of said complex tone qualities, a third electronic tube connected between some of said tone generators and the control element of said second amplifier tube substantially in parallel with said first amplifier tube, and a second network between the control element of said second tube and the output from said third tube, including resistances and reactances proportioned to emphasize portions of the tone frequencies other than those emphasized by said first mentioned network interconnecting said first and second amplifier tubes.

4. In an electronic musical instrument having a plurality of musical tone generators each producing an output tone of complex quality, a tone shaping circuit comprising a combining amplifier tube and a plurality of substantially parallel electronic paths interconnecting said combining amplifier tube and a plurality of tone generators, means in each of said substantially parallel paths accentuating selected tone frequencies of each of said output tones, and variable impedance means in one of said substantially parallel paths determining the relative extent of accentuation.

5. A tone shaping circuit as described in claim 4 in which the variable means controlling the extent of accentuation comprises a switch and capacitors of different values connectable into circuit by said switch.

6. In an electronic musical instrument having a plurality of musical tone generators each producing an output tone of complex quality, a tone shaping circuit comprising a first amplifier tube, a network interconnecting said first amplifier tube and some of said tone generators, a combining amplifier tube, a network interconnecting the output of said first amplifier tube and the control element of said combining amplifier tube, said network including an impedance branch shunting part of said output to ground to discriminate against selected tones, a second amplifier tube, circuit means connecting the control element of said second amplifier tube to some of said tone generators, a low impedance path

connecting the output of said second amplifier tube to the control element of the combining amplifier tube, and a second path substantially in parallel with said low impedance path, said second path including a reactance element to emphasize certain tone frequencies.

FRANCIS M. SCHMIDT.
